UNITED STATES PATENT OFFICE.

GEORGE T. REED, OF BALTIMORE, MARYLAND, ASSIGNOR OF ONE-HALF
TO HORACE SLINGLUFF, OF BALTIMORE, MARYLAND.

BOTTLE OR JAR CLOSURE.

SPECIFICATION forming part of Letters Patent No. 769,960, dated September 13, 1904.

Application filed June 13, 1903. Renewed February 16, 1904. Serial No. 193,883. (No model.)

To all whom it may concern:

Be it known that I, GEORGE T. REED, a citizen of the United States of America, residing at the city of Baltimore, in the State of Maryland, have invented certain new and useful Improvements in Bottle or Jar Closures, of which the following is a specification:

This invention, which relates to bottle and jar closures, contemplates the production of a new and improved stopper, more especially designed for employment in connection with bottles and other necked glassware, the object of the invention being to supplant existing caps and internal stoppers which require specially-provided tools for their application to and detachment from the bottle by a very simple and inexpensive construction capable of being applied by hand to effectually seal the bottle and of being withdrawn by the use of an ordinary implement not necessarily designed for the purpose.

The nature of the improved stopper, the manner of inserting and withdrawing the same, and the advantages possessed by the construction are set forth in the following detailed description, which is to be read in connection with the accompanying drawings, illustrating the stopper in its preferred form of embodiment.

In the drawings, Figure 1 is a perspective view of the neck of a bottle with the improved stopper inserted therein. Fig. 2 is a vertical sectional view of the same. Fig. 3 is a perspective view of an expansible fibrous pulp thimble forming the outer member of the stopper. Fig. 4 is a vertical sectional view of said thimble. Fig. 5 is a perspective view of the inner non-expansible member of the stopper. Fig. 6 is a vertical sectional view of said inner member.

Referring to the drawings by numerals, 1 designates the neck of a bottle in the mouth of which my improved stopper is designed to be inserted.

2 is a thimble, preferably constructed from fibrous wood-pulp to have a cylindrical portion 3, open at its upper end and closed at its lower end by a bottom 4 and provided at its upper edge with an annular flange 5, in which

is an annular series of perforations 6 6. The 50 thimble, which, as stated, is preferably constructed of fibrous pulp, possesses the quality of expansibility to a limited degree, and the perforations 6 6 are provided to allow of this expansive quality at its upper or open end. 55 The thimble constitutes the outer member of the stopper and is formed at its exterior to closely conform to the aperture of the bottle-neck, as will be understood.

7 denotes a preferably metallic thimble 60 insertible within the pulp thimble and comprised of a cylindrical body 8, fluted or corrugated, and a top 9. Said top is preferably of arch form in cross-section, and a bail 10 is provided on said top by slitting the latter on 65 the lines 11 11 and depressing the top, as indicated at 12 12.

In practice the pulp thimble is inserted in the neck-aperture until the flange 5 contacts with the top of said neck, whereupon the metallic thimble is inserted in the pulp thimble until the top of the latter is coincident with the top of the flange 5 of the pulp thimble. The act of inserting the metallic thimble expands the pulp thimble to closely contact with 75 the wall of the bottle-neck aperture, the strain of said neck being relieved by the slight degree of contraction possessed by the corrugated metallic thimble. To this extent, therefore, the metallic thimble is yieldable, and with 80 uniformly-sized neck-apertures no contraction of the metallic thimble will take place, the contractible quality of the latter coming into play in sealing neck-apertures of unusual diameters. The provision of the perforations 85 in the flange of the pulp thimble insures equal expansibility of the pulp thimble throughout. Consequently a perfect seal is obtained at the upper edge of the bottle-neck aperture.

The members of the stopper may be inserted 90 by the exercise of hand-pressure, and to remove the stopper any handy implement may be inserted under the bail and by a prying action the metallic thimble is readily removed, after which the withdrawal of the pulp thimble 95 is easily accomplished.

It will be noted that the corrugations of the metallic thimble are formed on the walls

thereof parallel with the axis, and it is this arrangement of the corrugations that gives a slight yielding function of the metallic thimble and prevents by contraction any undue strain on the neck-aperture.

I claim as my invention—

1. A stopper for bottle-necks comprised of a flanged expandible thimble open at its upper end and having perforations around the flange 10 at its junction with the walls whereby to allow for the expansion of the flanged end.

2. A stopper for bottle-necks, comprised of a flanged expandible thimble for insertion into the neck-aperture, and a metallic thimble

having corrugations parallel with its axis inserted within the expandible thimble.

3. A stopper for bottle-necks and the like, comprised of a flanged expandible thimble, said flange having perforations, and a non-expandible corrugated thimble insertible in 20 the aforesaid thimble and provided with an integral bail to facilitate its removal.

In testimony whereof I affix my signature in presence of two witnesses.

GEORGE T. REED.
